UNITED STATES PATENT OFFICE.

GEORGE THOMAS LLOYD, LAWRENCE CUANE, AND WILLIAM ALEXANDER JONES, OF MELBOURNE, VICTORIA, AUSTRALIA.

CURTAIN SUPPORT.

Application filed May 21, 1924, Serial No. 714,945, and in Australia July 19, 1923.

This invention relates to improvements in curtain holders or supports and has been devised in order to provide a support or holder of greater utility than those at present in use and as means for hanging window curtains and various drapings usually combined with curtains in decorative schemes and which according to usual custom are suspended by various devices which in most cases are not self-contained.

The object of the present invention is to provide a simple yet more effective means for hanging from the one self-contained holder or support two or more rows of curtains together with the usual valance or other relief attachments employed at the top for decorative purposes and by which means curtain rings or rollers may be used or dispensed with as desired and the hanging of curtains with the best effects may be greatly simplified.

In addition the whole set of curtains and drapings may be attached to the invention before being raised into position and set on the brackets without the aid of steps or the like and may be taken down fully draped just as readily.

An essential feature embodied in the invention comprises means whereby the ends of the curtains can follow a curve rearwardly at the ends to the walls to conceal the ugliness of the rod or pole which at present is exposed to view and allows a space between the curtain and the wall which this invention overcomes and allows the curtain to be draped to the wall, thus considerably enhancing the appearance thereof and allowing various draping effects being obtained.

A further essential feature consists in forming the support of a plurality of rods supported by brackets at both ends, the bracket at one end being pivoted so that its arms can clear the rods when mounting or removing a curtain.

A further essential feature embodied in the invention consists in mounting on the tubular or other rail of the holder two spaced clamps adapted to be adjusted along the rail so that they receive the window brackets or arms and thus be accommodated to any width of window frame.

A further essential feature consists in the means employed for adjusting the tension

on the wires or other supports and for releasing the curtains from said wires or support.

A further essential feature consists in hingedly, pivotally or slidably mounting one of the end members of the holder having the spring or other arms supporting the wires and the ends of the curtains for the purposes hereinafter described.

A further essential feature embodied in the invention consists in mounting one or both ends of the wires in tubes within which is disposed a spring so as to compensate for the tension on the wires when holding the curtains, and these ends act somewhat as a bodkin for threading through the curtains.

In order that the invention may be more readily understood it will now be described with reference to the accompanying drawings in which:—

Figure 1 is a view in plan of one form of the invention.

Figure 2 is a view in plan illustrating one means of pivoting the end of the curtain support to allow of the fitting and removal of the curtains.

Figure 3 is a view in side elevation of the devices employed for mounting the curtain support to a window frame.

Figures 4 and 5 are views in side and front elevation of the means employed for fitting a supplementary curtain rod to the curtain support.

Figure 6 is a view illustrating an alternative construction of curtain support.

Figure 7 is a view in side elevation of the pivot means embodied in Figure 6.

Figure 8 is a sectional view of the means for mounting one or both ends of the curtain supporting wires to the support illustrated in Figure 6.

Figure 9 is a view in section of a curtain support having the curtain supports mounted thereon by means of roller hangers.

Figure 10 is a view showing the means to enable a wooden or other board being affixed to the rods, and

Figure 11 is a front elevation thereof.

In the construction illustrated in Figures 1, 2 and 3 end brackets 1 and 2 are spaced from each other and support metal rods or tubes 3, 4 and 5.

These brackets 1 and 2 are formed with forwardly projecting arms 6, 7, 8, the arms

6 supporting the rod 3, the arms 7 supporting the rod 4 and the arms 8 supporting the rod 5.

5 The arms 6 project only slightly inwardly so as to allow of clearance to mount the supporting clamps 9 to the bracket 10 fitted to the window or other frame.

10 The arms 7 and 8 project forwardly from the brackets 1 and 2 and curve inwardly as illustrated, the arms 7 and 8 of the rigid bracket 1 preferably rigidly supporting the curtain supporting arms 4 and 5 while the bracket 2 is pivoted at 11 on the arm 6, the end of the arm being formed with a hole 12 which when in line with the hole 13 in the bifurcated end member 14 of the rod or bar 3 may be rigidly held in locked position by a pin passing therethrough or by any other suitable fastening or locking devices.

20 The bracket 2 being pivoted enables the arms 7 and 8 to be swung clear of the ends of the tubes 4 and 5 to enable curtains to be fitted to or removed from the support, the reduced ends 16 of the arms 7 and 8 being adapted to enter the tube ends 15 when in locking position.

These brackets 1 and 2 have their arms 7 and 8 so shaped that the ends of the curtains follow a curve rearwardly to the walls 30 to conceal the ugliness of the ends of the supporting rod or pole which by the methods at present employed is exposed to view and also allows a space to occur between the curtains and the wall, which this invention entirely eliminates and this function forms an essential feature of the invention.

The curtain holder so constructed is supported to a window or other frame through the medium of the clamps 9.

40 These clamps 9 are adjustable along the rod or tube 3 and consist of a split sleeve member 17 surrounding the rod 3 and being clamped thereto by a screw 18 threading in the lugs 19 of said sleeve.

45 Formed on this sleeve 17 is a vertically disposed boss 20 formed with a rectangular hole adapted to receive the projection 21 of the bracket 10, the said bracket 10 being screwed or otherwise fastened by the member 22 to the window or other frame.

50 In order to provide auxiliary means for supporting an additional curtain on the support brackets 23 such as illustrated in Figures 4 and 5 may be mounted to the rods or tubes 3, 4 or 5.

55 These brackets 23 would be spaced from each other and being provided with a horizontal projection 24 on the inner surface, such projection would receive the respective ends of a curtain supporting rod or tube and thus rigidly support the same.

60 These brackets 23 are rigidly held to the curtain rods or tubes 3, 4 or 5 by means of the circular head 25 which slides on the 65 rods or tubes being formed with oppositely

projecting bosses 26 tapped to receive the locking screws 27.

70 It will be obvious that the rods or tubes 3, 4 and 5 are shaped to accommodate any wall or window projection or recess.

75 In the modification illustrated in Figure 9 the curtains may be suspended on hangers 28 fitted with rollers 29 working in grooves 30 formed on the upper edge of the rods or tubes 4 and 5.

80 In the construction illustrated in Figures 6, 7 and 8 a rod or tube 31 of any suitable material is provided and the ends of the tube or rod being supported by brackets 1 and 2 as above described, each comprising one, two or more arms 6, 7, 8, partially flexible or rigid.

85 These arms 6, 7, 8 are of different lengths and project forwardly, the inner arm 6 of each bracket being short while the arms 7 and 8 terminate in hooks 32, the two or more outer arms 7 and 8 extend from the outer portions of the brackets 1, 2, which at this point bend rearwardly of the wall, the arm or arms extending forwardly and then 90 curve inwardly, one in front of the other as illustrated.

95 Wires 33, 34 the ends of which are formed with loops or eyes 35, engage the hooks 32 and extend from the hooks at one end to the respective hooks at the other end of the holder while extending forwardly at the centre or other points from the holder tube or rod 31 is a rod or pin or other support 100 36 adapted to pass under the wires and prevent them from undue sagging when the curtains are mounted.

105 This support 36 may be mounted to the construction illustrated in Figure 1 if required.

110 When the curtains are mounted the outer arms 7 and 8 are so shaped that the ends of the curtains or valance follows the direction of the arms rearwardly to the wall thus providing an effective finish.

One or both ends of the curtain holding wires 33, 34 may connect springs 37 encased in tubes 38 so as to allow for resiliency or flexible compensation thereof to ensure the required tension.

115 One of the arm brackets is preferably pivoted such as by forming the end 39 of the supporting tube 31 with bifurcations 40 or flattened to receive the inner end of the end arm bracket 6 which is pivoted as at 120 39 to the said support by a pivot pin 39a and when in closed position the arm 6 rests against a stop 41 the parts being locked by a pin passing through the holes 42, holding the parts rigid while the curtains are hanging but when it is desired to remove the curtains the holding pin is removed allowing the bracket to move on its pivot inwardly at right angles to the length of the support so releasing the wires from the 125 130

hooks thus allowing of the ready removal of the curtains.

Figures 10 and 11 show the means employed for affixing a wooden or other board 5 to the rods for supporting the curtains and in order to accomplish this wooden cleats 43 are used which are composed of two pieces centrally divided as shown and which are adapted to be placed on the rod or rods and 10 retained thereon by means of screws 44 which pass from one cleat member to the other.

These cleats 43 may be spaced along the rods as desired according to the length of 15 board 45 to be supported and which is fastened thereto by any suitable means such as screws.

This board may be decoratively treated and shaped and covered with any material, 20 such as beadings, satin facings and so on.

We desire it to be understood that other suitable means for adjusting the tension and for the loosening of the wires or supports may be embodied without departing 25 from the spirit and scope of the invention, the essential features of which are above described.

What we claim as our invention and desire to secure by Letters Patent is:—

30 1. A curtain carrier comprising, a support rod, an end bracket on each end of the rod and inwardly curved curtain rod sup-

porting arms on the brackets, curtain rods supported between pairs of the curved arms, a pivoted connection between one end bracket and the support rod to permit ready mounting and removal of curtains. 35

2. A curtain carrier comprising, a support rod, an end bracket on each end of the 40 rod and inwardly curved curtain rod supporting arms on the brackets, curtain rods supported between pairs of the curved arms, a pivoted connection between one end bracket and the support rod to permit ready mounting and removal of curtains, clamps 45 adjustable along the rod and means carried by the clamps for attaching the rod to a window frame or the like.

3. A curtain carrier comprising, a support rod, an end bracket on each end of the 50 rod and inwardly curved curtain rod supporting arms on the brackets, and clamp means adjustable along the rod for attaching the rod to various widths of window frame, each clamp means including a split 55 sleeve for embracing the support rod, an apertured boss on the sleeve, and an attaching bracket carried in the aperture of the boss.

Signed at Melbourne, Victoria, Australia, 60
this 7th day of April, 1924.

GEORGE THOMAS LLOYD.

LAWRENCE CUANE.

WILLIAM ALEXANDER JONES.
